UNITED STATES PATENT OFFICE.

HERVEY DEXTER THATCHER, OF POTSDAM, NEW YORK.

GAME.

1,106,991.

Specification of Letters Patent. Patented Aug. 11, 1914.

Application filed October 13, 1913. Serial No. 794,920.

To all whom it may concern:

Be it known that I, HERVEY D. THATCHER, a citizen of the United States, residing at Potsdam, in the county of St. Lawrence, State of New York, have invented certain new and useful Improvements in Games, of which the following is a description, reference being had to the accompanying drawing and to the figures of reference marked thereon.

This invention relates to new and useful improvements in games.

One of the several objects of the invention is to provide a game somewhat similar to the well-known game of "checkers," but which is more instructive and harder to solve.

Other objects of the invention will appear in order in the following specification.

In the drawings,—Figure 1 is a plan view of a game board constructed in accordance with my invention and showing one embodiment thereof; Fig. 2 is a similar view, but showing a slightly different form; and Figs. 3 and 4 are perspective views respectively showing one of the playing units of each player.

Referring to the drawing, generally, it will be seen that my invention broadly comprises a game board which is divided into two playing fields, each field being sub-divided into a plurality of playing sections, and a bridge portion connecting the fields and comprising a restricted number of playing sections which connect the sections of the playing fields. Each player is provided with an equal number of playing units, and these units are respectively disposed on the playing sections of the fields. The players move these units in turn, and in a diagonal direction from one section to the other. As each player moves his units over the sections of the bridge portion, said units become kings, and are then capable of being moved in any direction. On account of the sections of the bridge portion being restricted in number, much difficulty will be occasioned by both players attempting to simultaneously pass their units over said bridge portion. To this end, I have provided a game board 5, which may be formed from any suitable material, but for the sake of cheapness I preferably employ cardboard. This board preferably consists of two connected circular sections, and each section is marked in any suitable manner

with a mutilated circle 6, the mutilated parts of the respective circles being arranged in registration, and at the juncture between the circular sections of the board. Each circle 6 constitutes the outline of a playing field, and each field is divided into a plurality of connected playing sections 7. In the form illustrated in Fig. 1 I have shown these sections as being polygonal in shape, while in Fig. 2 I have shown these sections as being circular in shape. These sections are arranged in transverse rows and disposed between the sections of the respective fields is a bridge portion 8, which consists of a restricted number of similarly constructed playing sections 9. In this instance, there are only three of these sections of the bridge portion, and said sections are arranged at the juncture of said playing fields. Each of the sections 9 is preferably stamped or otherwise marked with the word "Bridge" as indicated by the numeral 10. Each player uses a set of playing units 11 and 12 respectively, the units of the different sets being of different color.

In practice, each player positions his units on the playing sections 7 on his respective field, and at points farthermost away from the bridge portion 8. The players then move these units in diagonal directions from one section to the other, the moves, of course, being made in turn. Each player endeavors to "jump" one or more units belonging to his opponent. When this move has been made, the player takes the units which have been jumped. As the players move the units from one field to the other, it is necessary to cross the sections 9 of the bridge portion 8, and on account of these sections being restricted in number, much difficulty will, of course, be encountered by both players. As soon as the units of either player pass beyond said bridge portion and into the opponent's field, they become "kings" and these units are then capable of being moved in any direction. The game is then continued, the units being alternately moved until all of the units belonging to one player have either been taken or blocked from further movement.

Having thus described my invention, what I claim is:

1. In a game, a game board, including opposed fields, each field including a plurality of playing sections, and a bridge portion disposed between the fields and including a plu-

- rality of playing sections connecting the sections of said fields.
2. A game board divided into two fields, each field including a plurality of connected sections and a restricted number of other sections interposed between the sections of the respective fields.
3. In a game, a game board formed with opposed overlapping circles, a plurality of connected playing sections formed in each circle, and a restricted number of playing sections disposed at the junction of the two circles and connected with the playing sections of both circles.
4. In a game, a game board including opposed playing fields, each field being substantially circular in outline, a plurality of playing sections formed in each field, and a restricted number of other sections interposed between the sections of the respective fields.
5. In a game, a game board including opposed playing fields, each field being substantially circular in outline, a plurality of polygonal shaped playing sections formed in each field, and adjacent one another, and a restricted number of playing sections disposed intermediate the fields and connecting the sections thereof.
6. In a game, a game board including opposed fields, each field containing a plurality of connected playing sections and a bridge portion interposed between said fields and including a restricted number of playing sections connecting the sections of said playing fields. 30
7. In a game, a game board comprising two fields hingedly connected together, each field including a plurality of playing sections and a bridge portion formed on the board between the fields and comprising a plurality of playing sections connecting the sections of said fields. 35
8. In a game, a game board comprising opposed circular fields hingedly connected together, whereby said fields may be folded in opposed relation, each field comprising a plurality of connected playing sections and a bridge portion disposed intermediate said fields and comprising a plurality of playing sections connecting the sections of said fields. 40
- 45
- 50

In testimony whereof, I affix my signature, in the presence of two witnesses.

HERVEY DEXTER THATCHER.
